RADIO COURSE INDICATOR

Paul Hermannspann, Berlin, Germany, assignor
to Telefunken Gesellschaft für Drahtlose Tele-
graphie m. b. H., Berlin, Germany, a corpora-
tion of Germany

Application July 8, 1933, Serial No. 679,502
In Germany July 2, 1932

6 Claims. (Cl. 250—11)

This invention relates to a means to indicate both flying direction or course by radio reception on long waves as well as landing field strength by means of ultra-short wave reception.

5 Radio direction-finding means are known in the art wherein deviation from the course towards the left- or right-hand side is rendered perceptible by an optical instrument or a telephone. Equipment of this kind generally contains at least two antennæ, for instance, a non-directional antenna and a coil antenna with a mechanical or electric change-over switch whereby the connections of the antennæ are alternately switched or whereby the polarity of the coupling between 10 both antennæ is reversed at a suitable rhythm or rate. The output end of such an equipment contains as a general rule a telephone receiver and a needle instrument with center or midpoint adjustment or central zero.

15 Methods are known in the prior art for the purpose of insuring blind landing by means of reception of radio frequency signals. According to this method a transmitter with such a radiation is mounted at the landing point that the curves of constant field intensity are suitable landing curves. The receiver instrument required therefore generally comprises an antenna, an audion, 20 audio frequency amplifier, telephone and a needle instrument.

25 30 According to the invention the said two receiving equipments are so combined that some of the receiving means may be used commonly or jointly. The details of the invention itself and its mode of operation will be best understood from the following description when considered in view 35 of the accompanying drawing in which

Figure 1 shows diagrammatically a circuit embodying a preferred arrangement of receiving apparatus; and

40 Fig. 2 illustrates diagrammatically a modified arrangement.

Referring first to Fig. 1 an exemplified embodiment of the basic idea of the invention is shown in schematic form. The equipment on the radio-guided airplane comprises in this instance an open antenna A and a coil or loop aerial R. The mutual coupling of the two aerials, in a way well known in the art, is rhythmically changed by suitable mechanical or electrical reversing or 45 throw-over means K1. The radio-guided airplane outfit itself consists of a radio frequency part HF, a detector G and an audio frequency part NF. At the output end of the outfit, by way of a transformer T1, are connected, on the one hand, the telephone receiver Te1, and on the other

hand the needle instrument I1, the latter being united, for instance, by way of a suitable throw-over switch or commutator K2 operating in synchronism with device K1. In order that at the same time ultra-short waves intended for guidance in effecting a landing may be picked up, the lead from the antenna A to the radio frequency part HF of the radio-guided airplane receiver contains a small choke-coil L which serves to block the ultra-short waves. In coupling relation with antenna A by way of a small condenser C (of a value of, say, a few centimeters) is the audion U for ultra-short waves the output end of which is associated with the audio frequency part of the receiver outfit of the airplane. In series with the output transformer T1 of the airplane 10 radio outfit is a second output transformer T2 with which is united the instrument I2 and a telephone receiver Te2 required for the landing.

15 The demodulation energies from the detector U for ultra-short waves may be impressed upon the audio frequency amplifier NF, as shown in Fig. 1. On the other hand, these short wave energies may be combined with the long waves by means of apparatus as shown in Fig. 2. In the latter case but one tube G' is needed. In this scheme the oscillation circuit S1 tuned to the ultra-short wave, and the oscillation circuit S2 tuned to the longer wave are in series with the grid of audion tube G'.

20 25 In order to insure sharp separation of the two modulations at the output end of the receiver it is recommended to choose the modulation frequencies of the beacon transmitter and the transmitter serving as a guide in effecting the blind landing as dissimilar as feasible, say, for the former from 300—1000 cycles per second and for the latter for example 100 cycles per second, and to design the means with selective action at the output end of the receiver accordingly.

30 35 I claim:

40 45 50 55 1. An aerial navigation system adapted to indicate an airplane course by long wave reception and landing field intensity by ultra-short wave reception, comprising a loop aerial for the long wave reception and an open antenna common to the reception of both long waves and ultra-short waves, switching means for rhythmically and reversibly coupling the loop aerial with the open antenna, a radio frequency amplifier stage connected on the input side thereof to said switching means, a long wave detector connected to the output side of said amplifier, an ultra-short wave detector coupled to said open antenna, an audio-frequency amplifier having an input circuit

adapted to receive demodulation energies from both said detectors, an output circuit for said audio-frequency amplifier including independent means for filtering the demodulation energies of the long waves and of the ultra-short waves respectively, separate indicating devices each responsive to one or the other form of said demodulation energies respectively and means in the input circuits of the respective detectors for blocking the ultra-short waves in the one case and for blocking the long waves in the other case.

2. An arrangement to indicate an airplane course by long wave reception and landing field intensity by ultra short wave reception, comprising a loop aerial for said course indicator, a common open antenna, switching means for coupling the common open antenna with the loop aerial, a radio frequency amplifier stage connected to said switching means, a common audio frequency amplifier connected to the output of said radio frequency amplifier stage, a choke coil for blocking the ultra short waves connecting said open antenna to said switching means, a variable condenser connecting said open antenna to an audion, the output of said audion being connected to said common audio frequency amplifier stage, the output of said common audio frequency amplifier stage connected to a separate transformer for both the long and short waves, each separate transformer arranged to respond to a different modulated frequency, said transformer connected to a separate indicating device for both the long and short waves.

3. An arrangement to indicate an airplane course by a long wave reception and landing field intensity by ultra short wave reception, comprising a loop aerial for said course indicator, a common open antenna, switching means for coupling the common open antenna with the loop aerial, a radio frequency amplifier stage connected to said switching means, a common audio frequency amplifier connected to the output of said radio frequency amplifier stage, a choke coil for blocking the ultra short waves connecting said open

antenna to said switching means, a variable condenser connecting said open antenna to an audion, a first oscillation circuit tuned to the ultra short waves and a second oscillation circuit connected to the long waves, said first and second oscillation circuits connected in series with the input of said audion, the output of said common audio frequency amplifier stage connected to a separate transformer for both the long and short waves, each separate transformer arranged to respond to a different modulated frequency, said transformer connected to a separate indicating device for both the long and short waves.

4. In an aerial navigation system an open antenna and a directional loop antenna, means in circuit with said antennæ for amplifying and detecting, in one case, short-wave radio frequency signals indicative of field intensity, and, in another case, long wave radio frequency signals indicative of direction, switching means for reversibly connecting said loop antenna to said open antenna, an audio-frequency amplifier so connected to said detecting means as to amplify the demodulated energies of both short wave and long wave signals, an output circuit for said audio-frequency amplifier including the primary windings of two transformers, said transformers having respectively different demodulation frequency response characteristics, and a plurality of independent responsive devices, one connected to a secondary winding of one of said transformers, and another to a secondary winding of a different one of said transformers.

5. A system in accordance with claim 4 and further characterized in that said amplifying and detecting means for the radio frequency signals have separate channels for the short waves and the long waves respectively.

6. A system in accordance with claim 4 and having switching means in circuit between one of said transformers that possesses its own demodulation frequency response characteristic and one of said responsive devices.

PAUL HERMANNSPANN.
